UNITED STATES PATENT OFFICE.

THOMAS J. WHALEN, OF NEW CASTLE, PENNSYLVANIA.

DESIGN FOR A TIRE.

51,829.

Specification for Design.

Patented Feb. 26, 1918.

Application filed January 2, 1917. Serial No. 140,315. Term of patent 14 years.

To all whom it may concern:

Be it known that I, THOMAS J. WHALEN, a citizen of the United States, and resident of New Castle, in the county of Lawrence and State of Pennsylvania, have invented a new and original ornamental Design for Tires, of which the following is a specification, reference being had to the accompanying drawings, forming a part thereof.

In the accompanying drawing, Figure 1

is a plan view of a section of a tire showing my new design, and Fig. 2 is a side elevation of the same.

I claim herein as my improved design—

The ornamental design for a tire, as shown.

In testimony whereof the said THOMAS J. WHALEN has hereunto set his hand this 19th day of December, A. D. 1916.

THOMAS J. WHALEN.
